**COMBINED HANDLE AND FLUID FLOW
METERING ORIFICE PLATE**

Arthur A. Hejduk, Cleveland, Ohio, assignor to The Meriam Instrument Company, Cleveland, Ohio, a corporation of Ohio

Continuation of design application Ser. No. 568, Jan. 11, 1966. This application Mar. 24, 1967, Ser. No. 6,370

Term of patent 14 years

(Cl. D23—27)

FIG. 1

FIG. 2

FIG. 3

FIGURE 1 is a top view of the combined handle and fluid flow metering orifice plate embodying the design of the present invention;

FIGURE 2 is a front view taken from the bottom in FIGURE 1; and

FIGURE 3 is a side view taken from the right in FIGURE 2.

The dominant features of the design reside in the portions shown in full lines.

This application is a continuation application of my parent U.S. design patent application Serial No. D. 568 filed January 11, 1966, and now abandoned.

I claim:

The ornamental design for a combined handle and fluid flow metering orifice plate, substantially as shown and described.
